UNITED STATES PATENT OFFICE.

DOUGLAS NIELD, OF PURLEY, ENGLAND.

ROTARY INTERNAL-COMBUSTION ENGINE.

1,199,489.

Specification of Letters Patent. Patented Sept. 26, 1916.

Application filed May 15, 1914. Serial No. 838,776.

To all whom it may concern:

Be it known that I, DOUGLAS NIELD, subject of the King of Great Britain, residing at Heath Cottage, Sunnydene Road, Purley, 5 in the county of Surrey, England, late of 12 Grand Parade, Epsom, in the county of Surrey, England, have invented new and useful Improvements in or Relating to Rotary Internal-Combustion Engines, of which the 10 following is a specification.

This invention relates to rotary internal combustion engines of the kind in which a rotor mounted within a casing is provided with piston elements, and wherein sliding 15 or pivoted abutments are provided for contact with the outer periphery of the rotor to inclose a space in which explosive gases are compressed and ignited, means being provided for admitting and exhausting 20 these gases at the proper times.

The object of the present invention is to provide an improved engine of this type, wherein a complete cycle of operations will be performed thoroughly and efficiently during 25 each revolution of the rotor, and which may be modified by multiplying certain of its parts in a manner which does not depart from the principle of the invention so as to permit the performance of a complete cycle 30 of operations in a fraction of a revolution of the rotor.

To this end the invention consists in the construction and combination of parts which are set forth fully hereinafter in the specification and claims and are illustrated in the accompanying drawings, in which:

Figure 1 is a side elevation, partly in section, of an engine constructed in accordance with the invention, the same being shown 40 provided with two combustion chambers; Fig. 2 is a vertical section through the same; Fig. 3 is a detail plan view of a part of the engine, partly in section, showing the securing means for one of the abutments, 45 when operative; Fig. 4 is a front elevation of a portion of one of the combustion chambers, showing in detail the abutment spring and segment; Fig. 5 is a detail sectional view of the engine casing and the piston 50 ring.

Referring to the drawing, wherein like reference characters indicate like parts throughout, *a* designates the annular casing of the engine which is rectangular in cross- 55 section and is made in two connected parts,

the division of the same parts being circumferential and at right angles to the shaft *g* of the engine, which latter is rotatably mounted in suitable bearings provided in the casing walls. The parts of the casing 60 are adapted to be bolted together, and the casing is provided, as shown, with two diametrically opposite explosion chambers *b*, which open through the inner surface of its circumferential wall. It is to be understood, 65 however, that the engine may in its simplest form be provided with a single combustion chamber. These combustion chambers may either be made integral with the casing, as shown, or separately constructed and attached thereto in suitable manner, this being an obvious mechanical expedient which should not require illustration. Each combustion chamber is constructed of suitable cross-section and is provided in its opposite 70 ends with swinging abutments *c* and *c'* mounted upon pivots *c*² in the walls of the combustion chamber.

The abutments *c* and *c'* are inclined toward each other and are in the form of 80 plates which fit the walls of the casing and are provided with springs *c*³ which act to maintain the innermost, free edges of the same in contact with the outer periphery 85 *d*² of the rotor *d*.

The rotor *d* comprises an annular hoop of rectangular cross-section which fits the inner surfaces of the sides of the casing and which is connected by means of radial arms *d*³ with the central boss or hub *f* attached to 90 the engine shaft *g*. The rotor is enlarged exteriorly at diametrically opposite points to provide the pistons *d*¹ and *d*⁴, which are intended for scavenging and intake purposes and for compression and motive impulse purposes respectively. For the sake of clearness, the piston *d*¹ will therefore be termed hereinafter the "scavenger piston" 95 and the other piston *d*⁴ will be referred to as the "explosion piston." The rotor is 100 adapted to turn in the direction of the arrow in Fig. 1, so the abutment *c* of each explosion chamber serves to back up each explosion and will be called the "explosion abutment." The other, co-acting abutment 105 *c'* will be termed the "compression abutment," owing to the fact that it assists the explosion abutment in retaining the combustible gases during compression. The abutments are thus adapted to be actuated 110

by engagement with the front and rear faces of the respective pistons (considering the direction of rotation of the rotor).

The casing *a* is provided with apertures 5 or slots *e*, which are located in the rear of each explosion chamber (considering the direction of rotation of the rotor) and which serve as exhaust ports. Each explosion chamber *b* is provided with an inlet valve 10 *m*, which may be of any usual construction, and with sparking plugs *n*, for igniting the charges of combustible fluid. Small automatic air inlet valves *p* provided with light closing springs, may be fitted to the casing 15 where shown, in order to obviate any tendency toward the formation of a vacuum behind the pistons, particularly during scavenging of the burnt gases.

The casing *a* is provided preferably with 20 one or more piston rings *h* (Figs. 2 and 5) in order to insure a gas-tight fit with the pistons of the rotor.

In the operation of the engine, which will be described fully hereinafter, it is essential 25 that the compression abutment *c*¹ shall be retained in inoperative position out of the path of the pistons during the firing and scavenging strokes or phases of each cycle. Therefore, a quadrant *c*² is provided exteriorly upon the pivot *c*² of this abutment and is adapted to be engaged by the inner end of a spring-pressed plunger *k*¹, normally, whereby the quadrant is held frictionally against movement and the said 30 abutment is maintained in inoperative position after it has been forced into the same by the explosion piston *a*⁴. A tripping lever *k* is suitably mounted upon the engine casing exteriorly thereof and extends radially, 35 its outer end being connected with the plunger *k*¹. The opposite end of the lever *k* is disposed in engagement with an operating cam *l*, which is connected with the engine shaft for movement therewith. This cam is 40 constructed so that it will move the lever *k* just after the scavenger piston *d*¹ has passed the abutment *c*¹ during each revolution of the rotor so as to trip the plunger *k*¹ and thus release the said abutment, whereby the 45 spring of the latter will cause it to follow the periphery of the rotor. The cam is adapted to maintain the lever in this position during the remaining half revolution of the rotor; that is, during the intake and 50 compression phases of each cycle.

The cross-sections of the pistons and the channeled shaped parts which receive the abutment may be of other than rectangular shape, for example, they may be of circular, 55 *V*, or *U* shape.

The invention is also applicable to pumps and air or gas compressors.

The operation of the engine, assuming in 60 the first place that there is only one explosion chamber and the corresponding abut-

ments and other parts, will now be described. In Fig. 1 of the drawings, considering only the explosion chamber at the left of this figure, the rotor is in a position wherein combustible gases have been drawn into the 70 explosion chamber by the scavenger piston *d*¹ and are about to be compressed by the explosion piston *d*⁴ during the next 90° of movement of the rotor in the direction of the arrow. During these two intake and compression phases, which occupy a semi-revolution of the rotor, the abutments *c* and *c*¹ will both be in contact with the rotor. When the front face of the explosion piston has thus compressed the gases in the explosion chamber, the gases will be ignited by the means provided for that purpose, whereby they will act upon the rear face of this piston, the compression abutment *c*¹ being maintained by the means previously 80 described in its inoperative position and the explosion abutment *c* continuing to follow the outer periphery of the rotor, whereby the explosion will have the greatest effect possible upon the explosion piston. The advance 85 face of the scavenger piston *d*¹ will, during the next 90° of movement of the rotor force the explosion abutment *c* outwardly and force the burnt gases past the inoperative abutment *c*¹ and through the exhaust ports *e*. 90 These four phases constitute one complete cycle, which embraces one revolution of the rotor. Now, assuming that there are two 95 explosion chambers, as shown in the drawing, the operation will be the same except 100 that there will be two motive impulses imparted to the explosion piston during each revolution.

Having thus described my invention, what I claim and desire to secure by Letters-Pat- 105 ent is:

A rotary internal combustion engine comprising a casing, a rotor journaled in said casing and having opposed exterior enlargements forming pistons, an explosion chamber provided upon the casing communicating with the interior of the same through its outer circumference, an intake valve provided in said chamber, pivoted explosion and compression abutments mounted within the 115 said chamber at the advance and rear sides of the same upon exteriorly projecting pivots, said abutments being adapted normally to bear against the outer periphery of the rotor to be operated by its pistons, means 120 for exploding the combustible gases within the said chamber after they have been compressed by one of the pistons, a quadrant secured to the pivot of the compression abutment exteriorly of the casing, a spring 125 pressed plunger normally engaging the said quadrant to secure the said abutment in inoperative position out of the path of the pistons during the firing and scavenging phases in each revolution of the rotor, and 130

means controlled by movement of the rotor for rendering the plunger inoperative to release the said abutment during the succeeding intake and compression phases, the casting being provided with an exhaust port in rear of the explosion chamber.

5 In testimony whereof I have signed my

name to this specification in the presence of two subscribing witnesses.

DOUGLAS NIELD.
